UNITED STATES PATENT OFFICE.

WILLIAM SIMMONDS, OF YONKERS, NEW YORK.

BOOK-HOLDER.

SPECIFICATION forming part of Letters Patent No. 369,475, dated September 6, 1887.

Application filed September 3, 1886. Serial No. 212,596. (No model.)

To all whom it may concern:

Be it known that I, WILLIAM SIMMONDS, of Yonkers, in the county of Westchester and State of New York, have invented a new and 5 Improved Book-Holder, of which the following is a full, clear, and exact description.

The object of my invention is to provide a cheap, practical, and convenient device to be applied to books for holding them open and in 10 convenient position for reading or copying; and the invention consists, principally, of a spring-clamp constructed to span the back of the book and grasp the leaves upon either side of the back and hold them firmly upon the 15 covers.

Reference is to be had to the accompanying drawings, forming a part of this specification, in which similar letters of reference indicate corresponding parts in both the figures.

20 Figure 1 shows my invention in front elevation applied to an open book; and Fig. 2 is an edge view of the same, showing the clamp provided with a standard.

The book-holding device A is made of considerable width to span the back B of the book 25 to hold the leaves C C flat upon the two covers, D D.

The device is composed of two plates of metal, a a', pivoted together upon pins b, and between 30 the two plates a a' are placed springs c, coiled around the pivots b, and arranged to spread the upper edges of the plates and close their lower edges. The plates a a' are correspondingly cut away in the center to form two sets 35 of jaws, d d, which grasp the leaves of the book on opposite sides of the back B, as shown in Fig. 1.

In the form of device shown in Fig. 2 the plate a' is provided with tube f, having a set-

screw, f', fitted in it, and in this tube is placed 40 loosely a pointed rod, h, which may be made fast by the set-screw f' and adjusted to suit the length of any book to which the device may be applied. This standard, composed of the said tube and rod, is for holding the book in 45 upright position, as shown in Fig. 2, in convenient position for reading or copying, so that the reader need not be troubled by holding the book in the hands or holding it open upon a stand, table, or other support.

I am aware that heretofore music-holders have been devised comprising a back plate and a section hinged thereto formed with two members or forks to press the sheets against the back plate, as in the Patent to H. R. Hoffman, 55 No. 289,658, December 4, 1883, and therefore lay no claim to such construction.

Having thus described my invention, what I claim as new, and desire to secure by Letters Patent, is—

As an improved article of manufacture, a book-holder composed of a back plate, a', recessed to form two side jaws, and a corresponding front plate, a, recessed to form two side jaws corresponding with the jaws of the back plate, 65 thus forming two sets of jaws or clasps to hold both pages of the book, the sets of jaws being spaced so that the binding of the book does not rest in contact with the connections between the jaws, the jaws of the front plate being acted upon by springs c at the two hinges which unite the front with the back plate, substantially as described.

WILLIAM SIMMONDS.
